UNITED STATES PATENT OFFICE.

SIDNEY HOLTZCLAW, OF KANSAS CITY, KANSAS.

CIGARETTE CASE.

1,422,975.

Specification of Letters Patent.

Patented July 18, 1922.

Application filed May 10, 1920. Serial No. 380,329.

To all whom it may concern:

Be it known that I, SIDNEY HOLTZCLAW, a citizen of the United States, and resident of Kansas City, Wyandotte County, State 5 of Kansas, have invented certain new and useful Improvements in Cigarette Cases, of which the following is a specification.

This invention relates to pocket cigarette cases, and more especially to cigarette cases 10 of that class having an opening in one side edge and means for feeding cigarettes one at a time to a point opposite said opening, and means for projecting the cigarettes aligned with the opening through the latter 15 so that it may be grasped and extracted from the case, and my object is to produce a device of the character outlined having a spring actuated feed bar for the cigarettes, adapted to be locked in retracted position 20 while the case is being charged, and a bar to overlie the cigarette and engage a part of the case for guiding the feed bar as the same performs its feeding function, said overlying bar being adapted to prevent the 25 cigarettes from being displaced in the case under the pressure of said feed bar when the cover of the case is opened, and to serve as a means of tripping the feed bar from engagement with the case so that it shall be 30 ready to perform its feeding function. Another object of the invention is to produce a cigarette case of the character described, which can be made and sold at low cost and which will operate efficiently and reliably. 35 With these objects in view the invention consists in certain novel and peculiar features of construction and combinations of parts as hereinafter described and claimed; and in order that it may be fully understood 40 reference is to be had to the accompanying drawing, in which:

Figure 1 is a section taken on the line I—I of Figure 2.

Figure 2 is a plan view with the cover 45 omitted except a small fragment thereof of its hinged end, and also showing the body of the case and a partition therein in section at said hinged end.

Figure 3 is a fragmentary perspective 50 view on an enlarged scale, of the feed bar.

Figure 4 is a section taken on the dotted line IV—IV of Figure 2, but on an enlarged scale.

In the said drawing 1 indicates the body 55 of a flat case adapted to be carried in one's

pocket and 2 is a cover thereof, the cover being hinged to the body of the case as at 3.

4 is a flat plate which may constitute an inturned portion of the front end of the body portion and 5 is a beveled latch projecting upward from said plate and adapted to engage the inturned edge of the cover, the latch having a thumb piece 7 projecting through the body portion of the case and adapted when depressed to trip the 65 catch from engagement with the flange 6 to permit the cover to be opened, and to apply yielding pressure on the catch to hold it in locked position; a flat spring 8 is arranged under plate 4 and bears against downturned 70 lugs 9 stamped from said plate 4, the spring being secured at one end to one of the lugs to guard against displacement.

Rearward of the plane of the hinged point 3, the rear portion of the body is provided 75 with a partition 10, the forward side of the partition being flush with the rear edge of an opening 11 formed in one side of the body portion and of sufficient size to permit a cigarette C, to slip endwise there- 80 through. The partition thus forms a guide for the cigarettes, but it also has another function hereinafter mentioned.

12 indicates a bar pivoted at 3 and interposed between the cover and the line of cigarettes C, and provided at its front end with a downturned arm 12^a terminating in a cam end 12^b adapted for engagement with an opening 12^c in plate 4, the arrangement being such that the bar 12 is held against 90 disconnection from plate 4 but can be readily disengaged therefrom by exerting an upward pull upon the bar.

At the opposite end of the partition 10 from the opening 11, the former is provided 95 with a longitudinal slot 10^a, and fitting against the rear side of said partition is a slideable ejector 10^b having an ejector finger 13 projecting through the said slot and adapted to overlap the end of each cigarette 100 at the opposite end thereof from the opening 11, as the cigarette is pressed against the partition 10. The slideable ejector has a rearwardly projecting pin 14 engaging a slot 15 in the rear wall of the body 1 of the case, and is connected by a retractive spring 16 to the case tending to hold the ejector finger in the position shown by Figure 2, and in order to overcome the resistance of said spring 105 and impart movement of the ejector finger 110

toward opening 11 for the purpose of projecting the interposed cigarettes through said opening, a thumb piece 17 is secured to the pin 14 and bears against the rear end of portion 1, externally thereof. When a cigarette is partly ejected from the case by the operation of said ejector, the latter is released and the spring 16 returns it to its original position so that when the operator 10 grasps and pulls the partly ejected cigarette out of the case, and the next cigarette is pressed through the action of the feed bar against the partition, said ejector finger shall overlap the end of said cigarette at the opposite side of the case from opening 11 and thus be ready to eject such cigarettes through said opening.

The feed bar hereinbefore mentioned and identified by reference character 18, extends 20 transversely in the case and is adapted to impart movement sidewise to one or more cigarettes within the case in order to press them successively against the partition 10, this action of the feed bar being effected by 25 means of a spring 19 bearing at its opposite ends against said feed bar and the lugs 9. The spring is shown in retracted or compressed position, and is of such character that it is capable of sliding the feed bar 30 toward the hinged end of the case until a cigarette engaged by said bar is arrested by contact with the partition 10.

The feed bar is provided with a rearward and upwardly projecting lug 20 adapted for 35 engagement with the opening 12^a of plate 4 to restrain said bar from movement while the cigarette case is being loaded or charged, during which time the bar 12 is of course raised. After the charging operation, the 40 bar 12 is lowered and pressed downwardly to cause its cam end 12^b to snap into opening 12^a and incidentally trip the lug 20 of the feed bar from engagement with said plate 4. As this occurs the spring 19 exerts 45 its pressure to cause the feed bar to press a cigarette or cigarettes in advance of it toward the partition 10.

To guide the feed bar against twisting action and also from undue upward tilting action under the pressure of spring 19, the upper wall of bar 18 which is preferably hollow for lightness, has stamped out of it upwardly projecting parallel arms 21 for engaging opposite sides of the guide and retaining bar 50 12, the arms 21 terminating in inwardly projecting ends 22 to underlie the bar 12, the portions 22 tending to prevent the tilting movements of the feed bar above mentioned.

When the case is loaded with one or more 60 cigarettes, the cigarette or the foremost one is held pressed by the bar 18 against partition 10 as above explained, so that such cigarettes can be ejected by proper sliding action of the finger 13 effected by applying 65 endwise pressure on thumb piece 17, as here-

inbefore explained. Pressure on thumb piece 7 trips the catch and permits the cover to be opened at any time, and should the case contain cigarettes the bar 12 will guard against their ejection accidentally or by pressure of spring 19, it being obvious that the pressure of the spring on the feed bar would result in bulging and dislodging the line of cigarettes, particularly when the case was well charged, if the bar 12 or its equivalent 75 was not employed to guard against such action. By the use of said bar therefore it is obvious that the case can be opened at any time without danger of dislodgment of the cigarettes.

From the above description it will be apparent that the case can be easily and quickly charged with cigarettes and that while being so charged, the engagement of the leg 20 with the opening of the plate 4 85 will relieve the operator of the necessity of holding the feed bar in retracted position, and that as soon as bar 12 is swung down to position, it frees the feed bar for action and is itself interlocked with said plate 4. 90 The other operations of the parts are common in this class of appliance and need no recapitulation herein. It is obvious that the invention is susceptible of change in minor particulars without departing from the 95 principle of construction involved or the scope of the appended claims.

I claim:

1. A cigarette case comprising a body portion having an inwardly projecting plate 100 at its front edge provided with an opening, a transverse guiding partition near its rear end and a side opening in a plane forward of said partition, a cover hinged to the body portion, latch mechanism to hold the cover closed, a transverse feed bar within the case, provided with a lug for engaging the opening of said inwardly projecting plate, a spring tending to impart movement to said feed bar towards the said partition, when said lug is not engaged with the opening of said plate, a bar hinged at the rear end of the body portion and adapted to lie within the case above a line of cigarettes therein to hold the latter against bulging upward within the case or out of the same, and terminating in an arm having a cam end for engaging in the said opening of said inwardly projecting plates and for tripping from engagement with said opening the said 115 lug of the feeder bar, said feeder bar having upwardly projecting arms engaging the side edges of the bar overlying the line of cigarettes, manually operable means for feeding a cigarette lying against said partition, partly through said side opening of the case, and yielding means for returning said manually operable means to initial position.

2. In a cigarette case, a spring actuated 130

feeder bar extending transversely and adapted to apply pressure against a cigarette within the case to impart movement in a sidewise direction thereto, and provided with upwardly projecting guidearms, and a guide bar lying within the case above the cigarettes therein and between said guide arms of the feeder bar; said feeder bar having a lug to engage an opening in a part of the case, and the other bar having an arm to trip the feeder bar arm from engagement with said opening in the case, said arms of the feeder bar having parts underlying the other bar to prevent upward movement of the feeder bar beyond a pre- 15 determined plane.

3. In a cigarette case, a body portion having an inwardly projecting plate at its front edge provided with a pair of down-turned lugs, a latch projecting up through said plate, a flat spring bearing against said lugs and said latch, and a hinged cover having an inwardly projecting flange at its free edge for engagement with said latch.

In testimony whereof, I affix my signature. 25
SIDNEY HOLTZCLAW.
